UNITED STATES PATENT OFFICE

OSCAR WARTEMANN, OF COLLEGE POINT, NEW YORK, N. Y.

DAM CONSTRUCTION

Application filed June 1, 1928. Serial No. 282,060.

This invention relates to improvements in concrete dam construction.

My invention has for its object to increase the efficiency of reenforced concrete structures of this character and I accomplish this object by constructing two or more spaced parallel straight or arched walls with connecting integral transverse walls.

One embodiment of my invention is illustratively exemplified in the accompanying drawings, in which,

Figure 1 is a plan view of a dam constructed in accordance with my invention;

Figure 2 is a transverse sectional view of the same, taken on the lines 2—2 of Figure 1;

Figure 3 is a plan view of a similarly constructed dam utilizing slightly modified connecting walls.

Referring to the drawings 10 and 11 denote respectively, the outer and inner walls of my improved dam, each wall comprising an arched reenforced concrete structure tapering towards the upper end, as illustrated in Figure 2. The ends of the walls 10 and 11 are suitably anchored in the embankments on the sides of the dam. The two walls 10 and 11 are further arranged with their bilge towards the body of water being retained and to increase their strength and to unite their combined resistance, transverse reenforced concrete walls 12 are disposed between the two walls. These transverse walls 12 are arranged so as to be disposed at an angle to the radii of the curve of the walls 10 and 11, as illustratively exemplified in Figures 1 and 2, or the transverse walls 12^a may be arranged coincident with the radii of the two walls.

It might be mentioned in connection with a concrete dam construction such as that forming the subject matter of this application, that the outer wall 10 is virtually the protecting or safety dam while the inner wall 11 constitutes the main dam by means of which the waters are initially retained. It is contemplated further that the cells 13 formed by the two walls 10 and 11 and the transverse walls 12 may be filled with earth and properly sodded while the upper faces 50 of the two walls are curbed and paved to

form roadways over which vehicles may conveniently pass, each wall providing for one way traffic.

Having now described the nature of my invention and the manner in which the same may be utilized, what I claim as new and desire to secure by Letters Patent is:

A dam comprising a pair of concentric arc-shaped walls disposed with their bulge in the upstream direction, each wall having a cross section tapering from the base towards the top, and V-shaped transverse walls integral at their apices and base ends, respectively, with the opposed faces of the two walls, the arms of the said transverse walls being disposed at an angle to the radii of the curve of the arched walls and having the portions at the apices inclined in the direction of the inner face of the upstream wall.

In testimony whereof I affix my signature.

OSCAR WARTEMANN.
